(57) **CLAIM**

The ornamental design for an exercise device, as shown and described herein.

DESCRIPTION

FIG. 1 is a top, front, and left side perspective view of an exercise device, according to the present invention;

FIG. 2 is a left side view of the exercise device of FIG. 1;

FIG. 3 is a front view of the exercise device of FIG. 1;

FIG. 4 is a right side view of the exercise device of FIG. 1;

FIG. 5 is a rear view of the exercise device of FIG. 1; and,

FIG. 6 is a top view of the exercise device of FIG. 1.

The bottom of the exercise device is flat and unornamented. The broken lines showing foot pedal assemblies of the exercise device in the drawing views are included for the purpose of showing the environment of the exercise device and forms no part of the claimed design.

The broken lines showing cup holder assemblies of the exercise device in the drawing views are included for the purpose of showing the environment of the exercise device and forms no part of the claimed design.

The broken lines showing the rollers and feet on the bottom of the exercise device in the drawing views are included for the purpose of showing the environment of the exercise device and forms no part of the claimed design.

The broken lines shown on the top side of the monitor assembly of the exercise device in the drawing views are included for the purpose of showing the environment of the exercise device and forms no part of the claimed design.

The broken lines showing a lever mechanism for adjusting the position of the seat of the exercise device in the drawing views are included for the purpose of showing the environment of the exercise device and forms no part of the claimed design.
